UNITED STATES PATENT OFFICE.

ADDISON A. ARTER, OF OMAHA, NEBRASKA.

DESIGN FOR A TIRE.

57,295.

Application filed August 28, 1919. Serial No. 320,536. Term of patent 14 years.

To all whom it may concern:

Be it known that I, ADDISON A. ARTER, a citizen of the United States, residing at Omaha, in the county of Douglas and State of Nebraska, have invented a new, original, and ornamental Design for Tires, of which the following is a specification, reference being had to the accompanying drawing, forming a part hereof.

Figure 1 is a partial plan view of a tire, showing the design on the tread thereof, and Fig. 2 is a partial transverse sectional view of the same, taken on the line 2—2 of Fig. 1.

I claim:

The ornamental design for a tire, as shown.
